ATTORNEYS

UNITED STATES PATENT OFFICE.

HENRY FREDRICK KELLNER, OF SILVER LAKE, KANSAS.

JETTY.

Application filed March 20, 1923. Serial No. 626,342.

To all whom it may concern:

Be it known that I, HENRY FREDRICK KELLNER, a citizen of the United States, and a resident of Silver Lake, in the county of

5 Shawnee and State of Kansas, have invented certain new and useful Improvements in Jetties, of which the following is a specification.

This invention relates to jetties and has 10 for its object the provision of a device which will effectually prevent the erosion of river banks and maintain the river along a predetermined course in its natural bed.

A further object of the invention is the 15 provision of a device adapted to be applied to a river bank for preventing deterioration of said bank and which may be simply and cheaply constructed while at the same time being effective for the purpose.

20 Another object of the invention is the provision of a plurality of devices adapted to be anchored in spaced relation along a river bank which is in the process of erosion by the swiftly moving waters, with the devices 25 being arranged at an angle of 45° to the direction of flow of the water and strung out in the direction of the current.

A still further object of the invention is the provision of a plurality of devices 30 adapted to be anchored in spaced relation along a river bank to prevent the erosion of said bank and which are connected together by a flexible means with the devices being arranged at an angle to the direction of flow 35 of the water and extended towards the direction of flow.

Other objects and advantages will become 40 apparent during the course of the following description.

45 The invention is illustrated by way of example in the accompanying drawings, in which,

Figure 1 is a longitudinal side view of a 50 plurality of sections on the jetty with each section triangular in cross section.

Figure 2 is a view in perspective of the 55 section of the jetty shown in Figure 1.

Referring to the drawings, 1 designates a river bank which is in the process of erosion due to the swiftly moving waters of a river. In order to prevent such erosion or deterioration of the bank it is necessary to provide some means, preferably of a skeleton structure, which will permit the water to pass through the same but will nevertheless check the current at this point and tend to main-

tain the current more directly in the center of the bed of the stream and away from the banks which are affected by the running water.

The sections of the jetty are triangular in cross section and are built up of three triangular endless bands 22. Each of the bands 22 is composed of three angle irons 23 provided with a plurality of perforations 24 spaced at least two feet apart and through which are passed flexible strands 25. The three bands are rigidly connected together by means of three angle irons 26 which are substantially sixteen feet long. These angle irons may be bolted or riveted to the end and intermediate bands 22 as may be desired. The bars 23 of the end bands are connected together by means of the angle irons 26.

The cables 25^a passing through the perforation at the extreme end of the triangular bands 22 are extended to a point on the bank which is secured to the post or deadman 11. The cables 25 are extended from the inner end of the triangular section as shown at 25^b and 80 pass through perforations on the inner end of a second triangular section of the jetty. As many triangular sections may be added to the cables to form the jetty as desired. The cables 25^b are substantially 8 feet long 85 or one half the length of the triangular section. The cables 25^a are secured in any approved manner to a dead man 11 located on the bank 1.

Jetties constructed in accordance with my 90 invention are adapted to protect a river bank to prevent erosion by the diversion of the current and is also adapted to provide for silt accumulations. The spacing of the cables is sufficient to permit the water to 95 pass readily through and deposit the silt or mud upon the lower side of the jetty and the weight of the frames is sufficient to cause said frames to sink readily without the necessity of requiring added weight 100 whereby the inner free end of the jetty will be lowered sufficiently below the navigation line to permit ships to pass and it is further noted that no sharp projections appear upon any portions of the completed jetty which 105 will in any way interfere with the navigation of the stream.

The jetties may be made of any length, but I prefer to construct them at least from eighty to one hundred feet.

While I have disclosed the sections as constructed of angle irons, I wish it to be

understood that any kind or form of material may be employed without departing from the scope of the invention.

The simplicity of the construction furnishes a jetty which may be cheaply made without affecting the usefulness and furthermore the same may be shipped to its point of destination unassembled in small bundles and readily set up at the river bank.

10 The completely constructed jetties are placed at least fifty feet apart along a river bank which is in the process of erosion and located at an angle of substantially 45° to the direction of flow of the current and 15 down stream. The flexible cables may be made of wire or any other material suitable for the purpose.

What I claim is:

A jetty composed of a plurality of frames,

each of said frames composed of a pair of 20 spaced perforated triangular metal bands of angle iron construction and an intermediate triangular band of similar construction, spaced angle iron bars rigidly connected to the triangular bands and spaced at 120° 25 apart, a plurality of spaced flexible strands inserted through the perforations in the metal bands, and extended beyond the ends of the frames and having other spaced 30 frames connected together by said flexible strands, with the strands passing through perforations in each of the triangular shaped bands of the frames so that the jetty will be composed of spaced rigid frames connected together by a plurality of flexible 35 strands arranged in triangular formation.

HENRY FREDRICK KELLNER.
